UNITED STATES PATENT OFFICE.

HERMAN A. SPERLICH AND JOHANNES HERMAN UHLIG, OF DETROIT, MICHIGAN.

MANGLE.

Application filed September 6, 1921, Serial No. 496,703. Renewed August 22, 1927.

This invention relates to that type of ironing machines in which the dampened clothes are drawn over a smooth heated surface by means of a padded roller, and the object of this invention is to produce a mangle of this character in which the stationary surface shall be substantially horizontal and be heated in the most economical manner, in which the padded roller may be caused to move substantially vertically away from the heated surface by mechanism connected to the operating motor upon the application of minimum pressure to a control lever, and in which the outer surface of the padded roller is so freely exposed for a maximum period of time that any moisture absorbed by the padding thereon while in contact with the work has ample time to evaporate before again coming in contact with wet clothes.

This invention consists of a horizontal padded roller and means to rotate it, of a smooth shoe mounted below the roller and means to heat the shoe, the upper surface of the shoe being cylindrical and substantially conforming to the roller, of mechanical means to elevate the roller, and of a control device actuated by the operator for causing the means for rotating the roller to drive the means for elevating it.

It further consists of manually operable means for elevating the roller independent of the mechanical means therefor.

It also consists of mechanical means for returning the roller into contact with the shoe upon the succeeding actuation of the control device by the operator.

It also consists in the details of construction illustrated in the accompanying drawings and particularly pointed out in the claims.

In the accompanying drawings, Fig. 1 is a perspective view of this improved mangle. Fig. 1^a is a detail showing the spring to return a pedal. Fig. 2 is a detail of the gears to drive the padded roller. Fig. 3 is an elevation of the left end of the mangle, the cap over the end of the frame being removed. Fig. 4 is a central vertical transverse section of the roller, shoe and burner, seen from the right. Fig. 5 is an elevation from the right of the mangle, parts thereof being broken away to show the details. Fig. 6 is a longitudinal section of the left end of the mangle. Fig. 7 is a similar section of the right end of the machine. Fig. 8 is a

front view substantially in section of the entire machine. Fig. 9 is an elevation of the plate supporting the dog which releases the clutch. Fig. 10 is a section of the same. Fig. 11 is a cross section of a coupling pin for the control clutch. Fig. 12 is a perspective thereof.

Similar reference characters refer to like parts throughout the several views.

The present mangle is provided with legs 1, preferably bent from properly rolled bars, connected by the cross bars 2 as shown in Fig. 1. Pivoted to the front legs is a treadle 3 to which the lower end of the control rod 4 is connected. Cross rods 5 may be used to stiffen this structure.

Carried by the central transverse tops 6 of the legs are the end frames 7 and 8 between which the stationary shoe 9, shown in cross section in Fig. 4, extends, its end flanges 10 being secured to the frames by the bolts 11. The upper surface 13 of this shoe conforms substantially through the greater part of its width to the pad 14 on the roller 15, which is secured on the shaft 16 and is rotated thereby in the direction indicated by the arrow in Fig. 4. The front edge 17 of the shoe is cut away to form a cylindrical surface to freely admit the articles to be ironed, and a feed board 18, having end flanges 19, is secured to the end frames, as indicated in Fig. 4, to facilitate proper introduction of the clothes.

The burner pipe 21 extends beneath the shoe and has jet openings 22 which cause the flame to pass along the bottom of the shoe, pins 23 extending down from the shoe into the flame to render the flame more effective. A shell 24 extends beneath the shoe and burner tube and its openings 25 and 26 cause the flame to move transversely of the shoe. Any desired valve mechanism 27 (Fig. 6) may be employed. The lip 28 on this casing prevents the article being ironed from closing these openings 26 but does not prevent the hot gases from passing through the clothes to finally dry out the steam which may remain therein.

The roller shaft 16 is mounted in bearings 30 and 31 which are slidable in slots 32 and 33 in the frames. These bearings are movable up and down in the slots by means of the eccentric 34 at the right end of the machine and the crank 35 and crank pin 36 at the left end, both being mounted on the two-part roller-control shaft 37-38 whose oper-

ation will be described farther on. This shaft 37-38 is in two parts for convenience of manufacture and assemble and rotates one half turn at each actuation of the control mechanism therefor

The connecting rod between the crank pin 36 and the bearing 31 for the left end of the shaft 16 is largely a spring 40 which is screwed onto a spirally grooved hub 41 on 10 the bearing 31 and on a spirally grooved hub 42 of the eye 43 into which the pin 36 extends. These two hubs are kept in alignment by a rod 44 slidable therein. This spring and its mate at the other end of the 15 machine determine the pressure of the roller 15 against the shoe and while normally tight, these springs expand to permit the roller to yield sufficiently to allow clothes to pass through the machine. Should any 20 clothes become bunched, a touch on the control device causes a half-rotation of the control shaft and an elevation of the roller, while a second half-rotation of this shaft returns the roller to operative position. The 25 eccentric yoke 46 on the eccentric 34 has a spirally grooved hub 47 which receives the spring 40 at that end of the machine and the action is similar to that just described.

The frame 7 has a bracket 49 on which the 30 electric motor 50 may be mounted, and its shaft 52 is mounted in the bearing 53 carried by the removable front plate 54 of this frame. On this shaft is a worm 55 which meshes with the worm gear 56 attached to 35 the sleeve 57 which is loose on the part 37 of the control shaft. I have shown (in Fig. 7) this worm gear screwed onto the outer end of the sleeve, a toothed clutch disk 58 screwed onto the inner end of the sleeve, and 40 a sprocket wheel 59 formed on the sleeve intermediate its ends, but these parts may all be integral if desired.

A pin 61 is mounted in the upper end of the frame 7, as indicated in Figs. 5 and 7, 45 and the yoke 62 thereon carries a drive shaft 63 at its lower end, to which the sprocket wheel 64 and pinion 65 are connected. A chain 66 connects the sprocket wheels 59 and 64 and the pinion meshes with the gear 67 on 50 the end of the roller shaft 16. The grooves 32 and 33 in which the bearings 30 and 31 are slidable are curved around the axis of the shaft 63 as a center when that is in a position shown in Fig. 5, when the pinion 65 55 meshes with the gear 67. This permits the roller shaft to be moved up and down without disengaging the driving gears therefor. The arc through which the shaft 63 swings has no effect on the engagement of the 60 sprocket chain and its wheels.

Mounted in the frame 7 is another shaft 69 on whose outer end is a handle 70 by which this shaft may be turned. On the inner end of this shaft is a cam 72 which engages the yoke 62 and normally holds it

in the position shown in Fig. 2, but when the handle is swung to the left in Fig 2, to free this yoke 62, the weight of the yoke and the pressure between the driving gears causes disengagement of the gears so that 70 this handle controls the rotation of the roller.

The mechanism which connects and disconnects the control shaft 36-37 to and from the motor and notched clutch disk 75 58 is as follows. Mounted within the frame 7 on the shaft 37 is a clutch frame 74 in which a clutch head 75 is rotatable in the direction of the arrow thereon in Fig. 5. Endwise movement of this clutch head 75 80 is prevented by the clutch disk 58 and by the eccentric 34, while endwise movement of the clutch frame is prevented by the clutch head 75 and the eccentric 34. Rotation of the clutch frame is prevented by a lug 78 on the 85 bracket 79 which lug extends into a notch 80 in the clutch frame 74. The clutch head is provided with guides 76 between which are the T-shaped grooves in which the clutch keys 77 are slidable. I prefer to form the rear 90 walls of these slots radial and while the inner ends of the clutch keys are of the same thickness as the clutch disk 58, the shoulders 75^a thereon project above the plane 95 of the clutch head and frame. See Fig. 10.

The clutch keys 77 are normally in the position shown in Fig. 5. Whenever the treadle 3 is depressed, the control rod 4 pulls down the control lever 82 (Fig. 5), which is pivoted at 183 on the bracket 79 100 which is attached to the frame 7. This action causes the arm 188 on this lever to compress the spring 85 and to force the pin 86 inwardly. A pin 87 on the clutch frame supports the latch 83 which has an arm 84 105 in the path of the pin 86 and a hook 88 adapted to engage the end of the latch finger 89 which is pivoted on the pin 90 carried by the clutch frame. A spring 91 extends up from a lug 92 on this latch 110 finger to the pin 93 on the latch 83 to normally hold down this latch, while a second spring 94 extends from this lug 92 to a pin 95 on the clutch frame. Cams 96 are formed on the clutch head to return the 115 latch finger to normal position.

Whenever the roll 15 is to be raised, the treadle 3 and the control lever 82 are depressed, the pin 86 is forced inwardly against the tension of the spring 85, the 120 latch 83 is swung on its pivot against the force of the spring 91 and the upper end of the latch finger 89 is released from the hook 88. The latch finger is now swung toward the shaft 37 by the spring 94 and as 125 the latch finger bears against the adjacent clutch key 77 this key will be moved into the next notch 97 in the clutch disk 58 and this results in the clutch head 75 being carried around by the clutch disk. As 130

shown in Fig. 7, the clutch head and the eccentric 34 are secured to the outer part 37 of the control shaft by the key 98 so that when a clutch key 77 connects the clutch head to the clutch disk 58, the control shaft 37 rotates and the roller 15 moves up or down, as the case may be, from its last position.

In order to release the control shaft from the motor, the following described mechanism is employed. See Figs. 5, 9 and 10. Extending over the clutch head is a plate 99 secured to lugs 100 on the clutch frame, which plate carries a pin 101 on which the small cam arm 102 is mounted to swing in the path of the shoulders 75^a of the clutch keys 77. A lip 103 on this cam arm extends up above the plate and receives one end of the spring 104 which connects to the outer end of the cam arm 102, while a lip 105 on the plate extends down into the path of this cam arm.

When a clutch key 77 reaches the cam arm 102, its inner end is in a notch 97 in the cam disk 58 and its shoulder 74^a slides along the outer surface of the cam arm 102 and swings that arm inwardly until the pull of the spring 104 is sufficiently great to overcome the friction of the key 77 in its notch or until the arm 102 engages the lip 105 on the plate 99, when further rotation forces out the clutch key. In either case, the spring 104 swings out the cam arm 102 immediately after the key is released and holds this key from accidental engagement in a notch in the clutch disk. After the clutch head has turned until the key no longer engages the cam arm 102, the inclination of the key on a vertical plane is sufficient to prevent inward movement thereof.

When the clutch head has turned about ninety degrees, one of the lugs 96 thereon engages the latch finger 89 and pushes it outward, the upper end of the latch finger swinging the latch 85 against the pull of the spring 91 until the hook 88 has been passed. The clutch frame is provided with a pin 107 to limit the inward movement of the latch finger. In order to prevent the latch from swinging too far in either direction, the clutch frame may be formed with a hole 118 and the latch 83 with a finger 119 extending into this hole.

Two stop lugs 108 and 109 are provided on the clutch frame 74 to prevent rotation of the clutch head, the former preventing forward rotation and the latter rearward rotation of the clutch head when the clutch keys are in their outward positions shown in Fig. 5. A table 110 may be attached to the tops of the legs if desired.

To prevent clothes being burned should the motor stop while such clothes are between the roller and shoe, a pair of levers 112 are mounted on pins 113 on the frames

7 and 8, the inner ends of the levers being beneath the bearings 30 and 31 and the outer ends connecting to the rods 114 which extend down to the yoke 115 pivoted to the cross bars 2, as shown in Fig. 1. One arm 70 116 of this yoke extends forward so that the operator may step onto its forward end and thus force up the roller against the pull of the springs 40 sufficiently to release goods between the roller and shoe. In order to hold the roller elevated, the arm 116 may be formed with a notch 120 which may receive the edge of the adjacent leg 1 when this arm is depressed and swing sidewise to permit such engagement. This may be important to save the padding on the roller. As soon as the motor starts running again it lifts the roller so much higher than does the arm 116 that the load is removed therefrom which permits the spring 121 to swing 80 the yoke 115 to normal position. This yoke is preferably formed of a central tube with its ends bent forward and this tube is mounted on a rod 122 extending between the side bars 2 as shown in Fig. 1. 90

As the operator stands before the machine, both hands are free to spread the work so they will pass between the shoe and roller, the work falling onto the table 110 and therefore being convenient to the operator should a second passage be desirable. The roller is entirely free from the work for about three fourths of its circumference, which permits the moisture in the padding to evaporate freely, there being no shield or obstacle to prevent such evaporation. Should the goods become bunched, slight pressure on the treadle 3 instantly causes the roller to rise to free the work and permit the goods to be straightened out. With eight teeth in the clutch disk 58, the pinion 65 one eighth the diameter of the gear 67, and the sprocket wheels at the ratio of 7 to 10, the roller 15 may turn through from thirty to forty degrees from the time the pedal 2 is depressed until the roller reaches its maximum elevation, or in time, a small fraction of a second. 100

The details and proportions of the various parts may all be changed by those skilled in the art without departing from the spirit of our invention as set forth in the following claims. 115

We claim:

1. In a mangle, the combination of a pair of side frames having guide slots, bearings slidable in said slots, a shaft rotatable in the bearings, a roller on the shaft, a shoe extending between the frames and fitting said roller, means to heat the shoe, a motor, a control shaft, clutch mechanism between the motor and control shaft, driving mechanism between the motor and the roll shaft, a pair of eccentrics on the control shaft, resilient connecting devices between said 120 125 130

eccentrics and the bearings for the roll shaft whereby the roll may be elevated or pressed against said shoe, said rods embodying end bearing members and springs connecting them, and manually operable means to cause the operation of the clutch.

2. In a mangle, a pair of frames having upright guide slots, legs for said frame, a roller and bearings therefor slidable in said slots, a lever pivoted intermediate its ends to each frame and having one end beneath the adjacent bearing for the roller, a pair of levers pivoted to said legs and a cross bar connecting them, links connecting them to the levers pivoted on the frames, one of the levers pivoted on the legs comprising a pedal having a notch to receive an edge of a leg to lock said pedal in a depressed position.

20 3. In a mangle, a horizontal roller and bearings therefor, a shoe below the roller and means to heat the shoe, a driving shaft and means to rotate the shaft, a swinging yoke to support the shaft, a pinion on the shaft, a gear connected to the roller and adapted to mesh with the pinion, and manually operable means to swing said yoke to move the pinion into and out of mesh with said gear.

30 4. In a mangle, a horizontal roller and bearings therefor, a frame having slots to receive said bearings, a shoe below the roller and means to heat the shoe, a driving shaft and means to rotate the shaft, a swinging yoke to support the shaft, said yoke being pivotally supported on the frame, a pinion on the shaft, a gear connected to the roller and adapted to mesh with the pinion, manually operable means to swing said yoke to cause the pinion to mesh with said gear, and means to move said roller into and out of engagement with the shoe.

45 5. In a mangle, a horizontal roller and bearings therefor, a frame having slots to receive said bearings, a shoe below the roller and means to heat the shoe, a driving shaft and means to rotate the shaft, a swinging yoke to support the shaft, said yoke being pivotally supported on the frame, a pinion on the shaft, a gear connected to the roller and adapted to mesh with the pinion, manually operable means to swing said yoke to cause the pinion to mesh with said gear, and means to move said roller into and out of engagement with the shoe, said slots being arcuate with the axis of the shaft as a center when the pinion and gear are in mesh.

60 6. In a mangle, the combination of a pair of side frames having guide slots therein, bearings slidable in said guide slots, a shaft rotatable in the bearings, a roller on the shaft, a shoe extending between the frames, means to heat the shoe, a motor to drive the

shaft, motor driven means to raise the roller from the shoe, a lever pivoted on each frame and having one arm extending under the adjacent shaft bearing, but disconnected therefrom, and a lever connected to said levers to actuate the same to raise the roller from the shoe independently of said motor driven means.

70 7. In a mangle, a horizontal roller and a shaft therefor, an electric motor to drive the roller, bearings for the ends of the shaft, a shoe below the roller and means to heat the shoe, a control shaft below the shoe and eccentric members thereon, resilient connecting devices between said eccentric members and the bearings for the roller shaft whereby the roller may be raised or lowered as the control shaft is rotated said connecting devices comprising bearing members and springs between them, and means for intermittently connecting the motor to the control shaft.

75 8. In a mangle, a horizontal roller and a shaft therefor, an electric motor to drive the roller, bearings for the ends of the shaft, a shoe below the roller and means to heat the shoe, a control shaft below the shoe and eccentric members thereon, resilient connecting devices between said eccentric members and the bearings for the roller shaft whereby the roller may be raised or lowered as the control shaft is rotated said connecting devices comprising bearing members and springs between them, and means for intermittently connecting the motor to the control shaft comprising a clutch and means to disengage the clutch at each half rotation of the control shaft.

80 9. In a mangle, a horizontal roller and bearings therefor, an electric motor, a shoe below the roller and means to heat it, a sprocket wheel driven by the motor, a gear connected to the roller, a pinion meshing with the gear, a second sprocket wheel connected to the pinion, a chain connecting the sprocket wheels, guides for the roller bearings wherein they may be moved up and down, and means operable by the motor for moving the roller toward and from the shoe.

85 10. In a mangle, a roller and bearings therefor, an electric motor, a shoe below the roller and means to heat it, gear mechanism connecting the roller and the motor whereby the motor may drive the roller, guides for the roller bearings wherein they may be moved up and down, means operable by the motor for moving the roller toward and from the shoe and means to keep said gear mechanism in mesh while said roller is being moved toward and from the shoe.

HERMAN A. SPERLICH.
JOHANNES HERMAN UHLIG.
